UNITED STATES PATENT OFFICE.

DARWIN W. SHEPARD, OF DENVER, COLORADO, ASSIGNOR TO THE SHEPARD PATENT CEMENT MINE AND TUNNEL TIMBERING COMPANY, OF DENVER, COLORADO.

METAL-REINFORCED-CONCRETE TIMBERING FOR MINE-SHAFTS.

992,073.

Specification of Letters Patent.

Patented May 9, 1911.

Application filed January 25, 1909. Serial No. 474,004.

To all whom it may concern:

Be it known that I, DARWIN W. SHEPARD, a citizen of the United States, residing in the city and county of Denver and State of Colorado, have invented certain new and useful Improvements in Metal-Reinforced-Concrete Timbering for Mine-Shafts; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in metal reinforced timbering, more specially intended for use in mining shafts or other shafts which require timbering.

The metal reinforcement employed in this invention is similar to that set forth in my co-pending application entitled metal reinforced concrete timbering for mine tunnels, Serial Number 474,005 the structure being composed of beams in which metal rods are longitudinally disposed, being employed in connection with metal stirrups transversely arranged.

Having briefly outlined my improved construction I will proceed to describe the same in detail, reference being made to the accompanying drawing, in which is illustrated an embodiment thereof.

In this drawing Figure 1 is a top plan view of my improved timbering construction for mining shafts, showing the same arranged for a double compartment shaft. Fig. 2 is a side elevation of the same. Fig. 3 is a view illustrating the metal reinforcement of one of the beams, the shape of the latter being indicated by dotted lines. Fig. 4 is a view looking in the direction of arrow 4, Fig. 3. This is a view looking in the direction of either arrow *a* or *b*, Fig. 1—the metal reinforcement of the beam only being shown. Fig. 5 is a top plan view of the structure arranged for a single compartment shaft. Fig. 6 is a view similar to Fig. 3, illustrating the metal reinforcement of a beam of slightly different construction from that shown in Fig. 3, as indicated by the dotted lines which show the form or external shape of the beam. This is a view looking in the direction of arrow *a*, Fig.

1—the metal reinforcement, however, only 55 being shown. Fig. 7 is a view looking in the direction of arrow 7, Fig. 6. Fig. 8 is a cross section taken on the line 8—8 Fig. 7.

The same reference characters indicate the same parts in all of the views.

Referring first more particularly to Figs. 1 and 2, let the numeral 5, designate each of a series of beams arranged one above another, and constituting a vertically disposed central partition of a double compartment 65 shaft, such as illustrated in Figs. 1 and 2. The extremities of these beams are reduced, forming tenons 6, which are engaged by the inner extremities 8 of the beams 7. These extremities 8 are plain, while the opposite 70 extremities of the beams 7 are reduced, forming tenons 9, which are engaged by corresponding tenons 10 of the end beams 12, the tenons 9 and 10 together being just equal to the thickness of one of the beams. It is 75 believed that this construction will be readily understood without further explanation in detail since the manner of timbering the two compartments of the shaft will be readily understood from an inspection of the drawing.

The metal reinforcement of each beam 12 consists of rods 13 and 14, arranged lengthwise of the beam, and having their body portions located near the inner surface of the 85 beam when the latter is employed for shaft timbering purposes, in order to give the beam the greatest strength where it is subjected to the maximum strain. The rod 13 of each beam 12 has its extremities formed 90 into eyes 15, each of which is located in one of the tenons 10 of the beam. As shown in the drawing, each beam 12 is provided with two rods 14, whose body portions lie in the same plane as the body portion of the rod 13, 95 and whose extremities are bent outwardly, as shown at 16, for anchoring purposes. These reinforcing rods are embedded in the beam, being placed in the mold when the beam is formed.

Cooperating with the reinforcing rods 13 and 14, are metal stirrups, whose closed extremities are designated 17, the same being located adjacent to the inner surface of the beam or that where the main portions of 105 the reinforcing rods are located. The sides 18 of the stirrups extend outwardly from the extremities of the part 17, and are bent

toward each other, as shown at 19, for the purpose of better anchorage. These metal stirrups are also inclined as they extend outwardly from the inner surface of the beam, 5 one set of the stirrups being inclined toward one end of the beam, and another set of stirrups being inclined toward the opposite end of the beam. As shown in the drawing, each set of stirrups in the sense just used, 10 consists of three,--the sets being arranged on opposite sides of a plane passed transversely through the center of the beam.

The metal reinforcement of each beam 7 is substantially similar to that of the beams 15 12, as just explained, except that the other reinforcing rod, which is designated 13 in the beam 12, is so much shorter than the beam 7, since the latter is devoid of one end tenon, and is designated 20. This rod 20 has a single eye 15, formed on one extremity thereof, while its opposite extremity is bent outwardly, as shown at 21. The other rods constituting the metal reinforcement of the beam 7 are the same as in beam 25 12, and are, therefore, given the same reference characters.

The tenons 10 of the various beams are provided with apertures 22 adapted to receive vertically disposed rods 23, which are 30 inserted therein when the beams are assembled for shaft timbering purposes.

The partition beams 5 are each provided with a centrally located reinforcing rod 24 35 whose extremities are bent into eyes 25, located within the tongues or tenons 6. The tenons of these beams 5 are also provided with openings designated 26, through which rods 27 are passed when the beams are assembled to form the central partition of the 40 double compartment shaft.

In timbering a single compartment shaft, such as shown in Fig. 5, the partition timbers 5, of course, are not required. In fact, the entire timbering of the shaft consists of 45 beams 12 so arranged that their tenoned ex-

tremities interlock in a manner that will be readily understood.

Having thus described my invention, what I claim is:

1. A timbering structure for shafts, comprising beams arranged one above another and whose extremities are provided with tenons on one side adapted to interlock, each beam being composed of concrete material having embedded therein reinforcing rods, longitudinally disposed, one of the said rods having its extremities embedded in the tenons of the bars, while the other rods are provided with bent extremities, terminating at a point above the body of the beams on the opposite side from the tenons, substantially as described. 50

2. A timbering structure for shafts, composed of beams arranged one above the other, and having tenons at their extremities on one side thereof, and arranged to interlock, each beam being composed of hardened plastic material, and having embedded therein longitudinally disposed, reinforcing rods, one rod of each beam having its extremities bent into eyes located at opposite extremities of the beam, within the tenons, while the other rods of each beam are relatively shorter and provided with bent extremities located near the ends of the body portion of the beams, on opposite sides from the tenons, the bars also having metal stirrups arranged in sets transversely thereof, the said sets of stirrups occupying an inclined position in opposite directions, and vertically disposed rods passing through the tenons of the beams and the eyes of the rods, substantially as described. 65 70 75 80

In testimony whereof I affix my signature in presence of two witnesses.

DARWIN W. SHEPARD.
